SIGNORS TO LLOYD A. UNGER, TRUSTEE.

INTERNAL-COMBUSTION ENGINE.

Application filed August 15, 1921. Serial No. 492,398.

This invention relates particularly to engines operating on heavy liquid fuel such as kerosene, distillate, and fuel oil, but is not restricted to such engines.

5 The invention aims to increase the thermal efficiency of internal combustion engines by vaporizing the fuel under pressure and heating and compressing the air necessary for combustion before mixing the two together. Preferably the air is heated and compressed in the cylinder before the vaporized fuel is admitted, and after admitting the fuel the mixture is further compressed before it is ignited.

10 15 The invention further aims to improve the fuel vaporizer by the use of an electric heating element, and by improved means of controlling the admission of liquid fuel and vaporized fuel to the heating element and cylinder, respectively.

20 Further aims and advantages of the invention appear in connection with the following description of a preferred form of the invention illustrated in the drawings.

25 Referring to the drawings, Fig. 1 is a side elevation of an internal combustion engine embodying the invention;

Fig. 2 is an end elevation of the same;

Fig. 3 is a vertical cross-section on the line 3—3 in Fig. 1, drawn to a larger scale, and

Fig. 4 is a cross-section on the line 4—4 in Fig. 3.

The engine shown in the drawings is of conventional four-stroke cycle type, having 35 four cylinders contained in a cylinder block 1 with a separable head 2, and furnished with a crank shaft 3 (see Fig. 3), connecting rods 4, pistons 5, inlet and exhaust 40 valves 6, exhaust manifold 7, ignition apparatus comprising spark plugs 8, and water pump 9, all of suitable form. The water pump discharge pipe 10 leads to the water jackets 11 surrounding the cylinders, 45 and the water circulates through the jackets and is discharged to the radiator (not shown) through a suitable manifold 12 running across the tops of the cylinders and constituting a part of the cylinder head 2.

50 The dimensions of the cylinders and pistons and stroke of the engine are such that the pressure in the cylinders at the end of the compression stroke is much higher than is usual in gasoline or kerosene burning

engines, preferably 125 pounds per square inch and over.

The liquid fuel (which may be gasoline, kerosene, distillate or fuel oil) is supplied from a suitable tank, through the supply pipe 13 and the fuel feed pump 14 to the several fuel vaporizers 15, of which in the illustrative embodiment of the invention there is one for each cylinder. (See Fig. 1.) A pressure relief valve 16 having an adjustable spring controls the fuel pressure and prevents excessive pressure on the fuel supply pipe. The vaporizers are surrounded by hot water from the cylinder jackets, which is kept circulating by means of the pump 9. The pump shaft 17 is driven from the engine by suitable gearing, such as the chain 17^a, and suitable sprockets on the crank shaft and pump shaft, as shown in Fig. 2.

55 The fuel vaporizers 15 are mounted in suitable chambers in the manifold 12, connected by suitable passages with the respective cylinders (see Fig. 3), and each comprises a valve 18 for controlling the admission of liquid to the heater element 19 and a valve 20 for controlling the admission of fuel vapor to the cylinder. In the illustrative embodiment of the invention the valves 18 and 20 are mechanically operated from the engine crank shaft by a half time cam shaft 21 through suitable gears and shafts 21^a so as to rotate at the same speed as the half time shaft 22 operating the inlet and exhaust valves.

60 In the form of vaporizer shown in the drawings, particularly Fig. 3, the heater element 19 has a steel shell which is held in place by a screw plug 23, which bears against a flange 24 on the steel shell. An insulator 25 of porcelain or other suitable material is fastened in the shell and supports the electrical resistance element 26 and terminal post 27 connected to one of its ends. Insulated wires lead to the terminal posts for supplying current to the heater. The resistance element 26 is a carbon rod all but the terminal end of which is contained in a steel case 28, from which it is spaced for the greater part of its length.

65 70 75 80 85 90 95 100 105 Liquid fuel is admitted through the pipe 13 and communicating passages to the space 22 surrounding the flange 24 of the heater element. The flange has a radial passage

through it, normally closed by the valve 18, and leading to an annular space 29 in the porcelain 25 surrounding the casing 28 for the resistance element. This annular space 5 envelops the casing 28 and opens into a space 30 in the vaporizer manifold which leads to the fuel port 31 in the cylinder. This port 31 is normally closed by the valve 20.

10 The stems 32, 33 of the valves 18, 20, respectively, are guided in bushings 34, 35, respectively, and are fitted with grooves and rings 36 for preventing liquid fuel or fuel vapor from escaping. The outer ends of 15 the valve stems are threaded and fitted with adjustable spring cups 37 and locking screws 38 for adjusting the throw of the respective valves independently. A plug 40 holds the closing spring 39 and valve 18 in place, and 20 a split housing 41 screwed to the manifold holds the spring and valve 20 in place. (See Fig. 4).

The valves 18, 20, are operated simultaneously by a double arm bell crank lever 42 having a cam arm 43 engaged once for every revolution of the shaft 21 by one of the cams 44 carried thereby. Each arm of the bell crank lever engages against the closed side of one of the respective spring cups 37 to 25 open the valves. The bell crank lever 42 is pivoted upon a shaft 45 journaled alongside of the cam shaft 21 in links 46 pivoted at their other ends on the shaft 21. Each link has an operating arm 47 slotted to 30 receive an adjusting sleeve nut 48 mounted on a pivot screw 49. An operating arm 50 is adjustably clamped on each adjusting nut 48 and connected for simultaneous actuation by a link 51. By adjusting the angular position 35 of the operating arm on the nut each pivot link 46 may be adjusted independently to suit the desired alinement for the shaft 45. A control rod 52 is attached to the link 45 to adjust the angular position of the shaft 45 and bell crank levers to suit the conditions of 40 operation of the engine. By shifting this control rod the position of the pivotal axis of the bell crank levers may be changed to vary their throw and thus vary the amount 45 of opening of the valves 18 and 20.

The operation of the engine is similar to that of the usual four-stroke cycle internal combustion engine of the fuel injecting type 55 having a pump for forcing the fuel into the cylinders and wherein the air is taken in on the suction stroke and the products of combustion are discharged on the exhaust stroke through suitable valves operated by cams or other suitable means driven from the crank 60 shaft of the engine.

Preferably the dry air is compressed in 65 the cylinders to a pressure corresponding to a temperature of approximately the vaporizing temperature of the fuel before the vaporized fuel is admitted, whereupon the va-

porized fuel is admitted under a pressure in excess of the pressure of the air at that point in the compression stroke, and the compression of the mixture continued to a pressure short of the pressure at which the mixture will pre-ignite. The pressure of the vaporized fuel may be controlled by varying the relief valve spring 16, and the amount of fuel may be varied by adjusting the valve opening under manual control.

The invention is not restricted to the apparatus shown in the drawings, nor to the particular method of operation described.

We claim the following as our invention:

1. In an explosion engine, having a working cylinder, means for vaporizing liquid fuel comprising an electric heating element, fuel passages leading to said heating element and from said heating element to said cylinder, and valves in said passages actuated by the operation of said engine to control the flow of liquid fuel to said vaporizer and the flow of fuel vapor from said vaporizer to said cylinder.

2. In an explosion engine, having a working cylinder, means for vaporizing liquid fuel comprising an electric heating element, fuel passages leading to said heating element and from said heating element to said cylinder, and valves in said passages actuated by the operation of said engine to control the flow of liquid fuel to said vaporizer and the flow of fuel vapor from said vaporizer to said cylinder, said valves operating to open and close simultaneously.

3. In an explosion engine, having a working cylinder, means for vaporizing liquid fuel comprising an electric heating element, fuel passages leading to said heating element and from said heating element to said cylinder, variable throw valves in said passages actuated by the operation of said engine to control the flow of liquid fuel to said vaporizer and the flow of fuel vapor from said vaporizer to said cylinder, and means for controlling the amount of opening of said valves.

4. In a fuel vaporizer for explosion engines, an electrical heating element, passages for fuel leading to said element and from said element to said engine, valves in said passages and operating means for said valves comprising a lever, means for oscillating said lever from a rotating shaft, and means for changing the pivot point of said lever to vary its amount of oscillation and the throw of said valves.

5. In a fuel vaporizer for explosion engines, an electrical heating element, passages for fuel leading to said element and from said element to said engine, valves in said passages, said valves having springs tending to hold them closed, and operating means for said valves comprising a lever having two arms, adjustable connections between

said arms and valves, means for oscillating said lever from a rotating shaft, and means for changing the pivot point of said lever to vary its amount of oscillation and the throw of said valves.

6. A vaporizer for liquid fuel comprising an electrical heating element surrounded by a casing and enclosed in a water jacketed

chamber, means for circulating hot water around said chamber, and means for maintaining the vaporized fuel in said chamber under pressure. 10

In testimony whereof, we have signed our names to this specification.

ROBERT F. LONABERGER.
CHARLES F. SANDS.
